UNITED STATES PATENT OFFICE.

JOHN L. THOMPSON, OF WATERBURY, CONNECTICUT.

SHOE-POLISHING MACHINE.

Application filed July 29, 1925. Serial No. 46,803.

This invention relates to shoe polishing machines, and more particularly to a machine capable of polishing the front, sides, and rear of a shoe simultaneously.

5 One object of this invention is to provide a machine of the above nature having four revolving brushes, one on each side, one in front, and one in the rear of a shoe, said brushes being continuously revolved by a 10 single coin-actuated motor.

A further object is to provide a machine of the above nature in which the side brushes are given a reciprocating backward and forward movement, and the front and rear 15 brushes are given a reciprocating up and down movement.

20 A further object is to provide a machine of the above nature comprising a pair of connected units, one for polishing black shoes and the other for polishing tan shoes.

25 A further object is to provide a machine of the above nature so arranged as to permit the successive polishing of both shoes of a pair, upon the insertion of a single coin.

30 A further object is to provide a machine of the above nature having adjusting means to allow the polishing of either high or low shoes.

35 With these and other objects in view, there has been illustrated on the accompanying drawings, one form in which the invention may be conveniently embodied in practice.

40 Fig. 1 represents a side sectional view of the shoe polishing machine.

Fig. 2 is a top sectional view of the same.

45 Fig. 3 is a perspective view of the shoe polishing machine, showing the two compartments adapted to polish black and tan shoes respectively.

Fig. 4 is a front sectional view of the machine showing the mechanism for operating the brushes.

50 Fig. 5 is a sectional view of one of the reservoirs for the liquid polish and also showing a roller adjacent thereto for transferring the polish from said reservoir to one of the shoe brushes.

Fig. 6 is a perspective view of the sliding carriage in which one of the side brushes is mounted.

Referring now to the drawings in which like reference numerals denote corresponding parts throughout the several views, the 60 polishing machine is housed in a casing A provided with a forwardly projecting base B, the latter having an opening C in its top through which a pair of foot treadles are adapted to project to receive the shoes 65 to be polished. The casing A is provided with an intermediate portion D having an inclined top section E in which is a slot 9^b for a forwardly extending operating handle 9.

The casing A is provided at its top with a reduced section F forming a bearing for a horizontal shaft 2, said shaft projecting in front of said section F and carrying 75 a dial knob 2^a at its forward end.

In order to support a motor H for driving the shoe polishing brushes, a shelf G is provided on the interior of the rear section of the casing, said motor being supplied with current from a suitable source, 80 not shown.

85 In order to unlock the machine to permit the motor H to be started, provision is made of a coin slot 3 at the right hand side of the casing A, into which slot the operator may deposit a coin of any predetermined denomination. The coin slot 3 is connected with a vertical chute 4, the bottom of which extends into a coin receiving box 5.

90 As will be clearly seen from Figs. 2 and 4, the casing A is divided into two compartments, the one at the right being used for polishing black shoes and the one at the left for polishing tan shoes. Since the mechanisms in the two compartments are identical, a description of one of them will be sufficient.

95 As will be seen best in Fig. 1, a tipple lever 5^a, which is pivoted at 5^b, is adapted to extend into said chute 4, so that the falling coin will cause said tipple lever to swing down about its pivot, thereby moving a catch 6 out from under a detent 7 projecting out from a vertical rack 8. If a coin smaller than the required value is dropped into the coin slot, it will fall down the chute until it strikes a spring M which will kick 100 said coin out of the chute.

The next operation will be to push down the handle 9 also located at the right hand side of the casing. The handle 9 is connected by a link 9^a to the rack 8, and consequently, the downward movement of said handle will cause the rack 8 to rotate a ratchet 10 in a counter-clockwise direction until a roller 11 on the end of an operating lever 11^a rides out of a slot 12 onto the outside of a cam 12^a.

The tipple lever 5^a is connected to the operating lever 11^a by a link 11^b. The cam 12^a is provided with a pin 12^b which is adapted to engage a rack 22, to be herein-after described. The rack 22 will thus be forced back against a U-shaped leaf spring 22^a, thereby disengaging the rack 22 from the ratchet 10 for about one third of a revolution and permitting the cam 12^a to turn freely.

When the roller 11 is forced down by the cam 12^a, the rear of the operating lever 11^a will rise and force a switch closing arm 13 upwardly. The arm 13 has a slotted end 13^a fitting over a pin 13^b on the end of the operating lever 11^a, and said arm 13 is constructed of any suitable insulating material. The top of the switch closing arm 13 is joined to a bell crank lever 13^c for closing a switch 14 and thus starting up the motor H for rotating all of the brushes simultaneously. A spring 14^a is connected to the lower arm of the bell crank lever 13^c to cause said switch to open rapidly when the operating lever 11^a resumes its original position.

Secured to both of the treadles 1, and located at the rear thereof, are a pair of small depending racks 15 and 15^a, which are adapted to mesh with gears 16 and 16^a respectively. The gear 16 is mounted on a shaft 17, and the gear 16^a is on a tube 17^a surrounding said shaft 17. The shaft 17 and the tube 17^a are provided with collars 18 and 18^a having lugs 18^b and 18^c which are joined to wires 19 extending upward and connected by springs 19^a to levers 20 pivoted at 20^a at the rear of the casing. The levers 20 have curved ends 20^b which hook over pins 21 mounted on the lower end of the rack 22, previously described, and are limited in moving downwardly by a stop 20^c.

In order to permit the shoe treadle 1 to be lowered to the correct position according to the type of shoe being shined, the dial shaft 2^a is provided at its rear end with a vertical gear 23 meshing with a horizontal pinion 24, said pinion 24 being mounted on the top of a vertical shaft 25 extending down through the casing A. The bottom of the shaft 25 is provided with a pin 25^a adapted to fit within a helical groove 26^a in a collar member 26, and said collar member 26 is slidable in a bracket 26^b.

By means of this construction, when the

dial knob 2 is turned clockwise, the collar member 26 will be raised and will thus adjust the height of a stop 26^c on the bottom of said collar 26, said stop serving to limit the downward movement of the treadle 1. The stop 26^c is adapted to be engaged by an arm 27 loosely mounted on the shaft 17, the arm 27 being interchangeably actuated by either of a pair of lugs 29 carried by said shaft 17 and said tube 17^a respectively.

When one shoe of a pair has been polished, the operator will remove his first foot from the treadle. This will cause the rack 22 to be drawn upwardly under the influence of a spring 21^a, whereupon the cam 12^a will rotate another third of a revolution. It will be understood that the pin 12^b will previously have moved out of engagement with the rack 22 to permit said rack to mesh with the ratchet 10.

When the second foot is placed on the treadle 1, the second shoe will be polished in the same manner as the first shoe. The user will then lift his second foot from the machine, allowing the treadle 1 to again rise. The wire 19 will thus be released permitting the lever 20 to again rise. The upward movement of the lever 20 will release the rack 22 which will move up under the influence of the spring 21^a. The rack 22 will at this time be engaging the ratchet 10 owing to the fact that the pin 12^b has moved out of engagement with said rack during the first one-third revolution of cam 12^a. Consequently, the upward movement of the rack will cause the cam 12^a to rotate another third of a revolution. This rotation will permit the roller 11 to again fall into the cam slot 12 and the catch 6 will again slip under the detent 7, thus locking the apparatus from further operation until another coin is inserted.

At the same time, the switch closing arm 13 will be drawn down by the operating lever 11^a to open the switch 14 and shut off the motor H. The machine will then remain idle until another coin is dropped into the coin slot 3, and the handle 9 is again pushed down.

When the treadle 1 of the left hand compartment is pressed down, the shaft 17 in that compartment will be caused to rotate a short distance, and the rotation of said shaft will pull down upon a cord 29^a connected to a collar 29^b on said shaft. The cord 29^a passes over a pulley 30 and is connected to a belt-shifting member 31, as clearly shown in Fig. 4. The belt-shifting member 31 is adapted to slide to the left along a fixed bar 32 until it is stopped by a pin 33, thereby transferring the belt 34^a from the idle pulley 34 to the left hand pulley 35, and thus connecting the brushes in the tan shoe compartment with the motor H.

In the other compartment, the depression

of the treadle 1 operates in the reverse manner, and the belt 34^a will be shifted to the right onto the other driving pulley 35. When the foot is removed from either of the 5 treadles 1, a pair of springs 36 which are connected at both sides of the belt-shifting member 31 will cause the belt-shifting member to pull the belt 34^a back to its original central position on the idle pulley 34, thus 10 instantly stopping the rotation of the brushes.

In order to transmit power from the motor H to the brush driving mechanism in either 15 of the compartments, provision is made of a pulley 35 rigidly keyed to a shaft 38 which has a grooved pulley 37 mounted thereon. A cord 38^a passes over said pulley 37 and thence around a pulley 39 mounted on a shaft 40. The shaft 40 is provided with 20 another pulley 41 which is connected by a cord 41^a to a third pulley 42 supported by the side walls of the casing mounted on a shaft 42^a.

Heel brush operating mechanism.—In 25 order to continuously rotate the brush at the rear of the shoe, the shaft 42^a has a pulley 43 mounted thereon and a cord 43^a passes around said pulley 43 and drives a pulley 44 on the heel brush 45. As will be 30 seen from the above construction, the heel brush 45 will be kept in continuous rotation so long as the treadle 1 is held pressed down by the foot of the user.

The heel brush 45 is adapted to be automatically and intermittently forced down 35 out of the way of the side brushes when the latter are at the rear end of their travel, and for this purpose, said heel brush 45 is loosely mounted on a shaft 46, said shaft 46 being carried by a pair of rods 47 rigidly 40 mounted on the shaft 42^a.

When the side brushes have reached the 45 limit of their rearward movement, an arm 49 on the shaft 42^a will be engaged by a lug 50 on one of the side brush carriages which will be hereinafter described. The arm 49 will thus be forced down, carrying 50 with it the heel brush 45.

In order to return the heel brush 45 to its 55 normal operating position when the side brush carriages have again moved forward, a spring 51 is provided, said spring being connected at its ends to an arm 52 secured to the shaft 42^a, and the forward section B of the casing respectively.

In order to supply liquid polish to the 60 heel brush 45 each time the pedal is depressed, provision is made of a roller 53 rotatably mounted on a rod 54 journaled in a movable carriage 55, said carriage 55 being given a reciprocating motion relative 65 to an automatic self-closing liquid polish reservoir 56, so as to cause said roller 53 to intermittently come into contact with the rear of the heel brush 45 and the reservoir

56. Whenever the operator's foot is removed from the treadle 1, the cord 57 with its connected carriage 55 will move to the right as viewed in Fig. 1 under the influence of the spring 59^a. The roller 53 will then 70 be seated in the reservoir 56. As most clearly shown in Fig. 5, the reservoir 56 is provided with a concave recess to fit about the roller 53, said recess being perforated to permit liquid polish to flow out and wet the 75 surface of the roller whenever the roller is seated in said recess. At such times, a rod 56^b is engaged by the roller 53 and forced inwardly against the pressure of a spring 56^c. This will cause a curved plate 56^d to 80 uncover the perforations in the recess 56^a. When the roller moves out of the recess, the spring 56^c automatically causes the reservoir to close.

The reciprocation of the carriage 55 is 85 caused by a cord 57 which is connected to the bottom of the carriage and has its other end connected to a depending crank arm 58 rigidly secured to the shaft 17. The movable polish-roller holding carriage 55 is 90 mounted to slide in ways 59 extending rearwardly from the base B.

Side brush operating mechanism.—In 95 order to polish the sides of a shoe, a pair of side brushes 74 are provided, said brushes being supplied with liquid polish from a pair of rollers 60 which are rigidly secured to a pair of vertical shafts 61. The rollers 60 are mounted on the same carriages 55 as are the rollers 53 and are adapted to receive a supply of polish from a pair of automatic self-closing reservoirs 60^a. The reservoirs 60^a are similar in all respects to the reservoir 56, previously described, and are adapted to supply the rollers 60 with polish 105 each time the pedal is raised.

Each of the side brushes 74 has a pulley 75 secured thereto and is mounted to rotate freely upon a shaft 76. The shaft 76 has a bushing 77 rigidly mounted thereon, and said bushing is adapted to be held by a set screw 78 upon a sliding rectangular carriage 79. The carriage 79 is adapted to slide within four parallel strips 77^a, said strips being secured, as by rivets 79^a, to 110 guide bars 86 which are slidably mounted in ways 87 attached to the casing.

In order to supply power for continuously 115 rotating the side brushes 74, the shaft 40 has secured thereto a mitre gear 62, which 120 meshes with a similar mitre gear 63 mounted on a shaft 64 at right angles to the shaft 40. The shaft 64 is provided with a pair of pulleys 65 and 66, the pulley 65 being connected by a cord 65^a to a pulley 67 keyed 125 to a shaft 68, the shaft 68 having a pinion 69 meshing with a large gear 70.

The gear 70, as most clearly shown in 130 Figs. 1 and 2, carries an upstanding stud 71 which is adapted to fit in a slot formed be-

tween a pair of parallel bars 72 on the side brush carriage. As will be evident from the above construction, the continuous rotation of the gear 70 with its stud 71 will cause the reciprocation of the side brush carriage 74^a as long as the foot of the operator is held upon the treadle 1.

The side brushes 74 are adapted to be pressed inwardly against the shoe being polished by a spring 85 connected to the bushings 77 on the two shafts 76. In order to keep the side brushes in continuous rotation, the pulleys 75 of said brushes are connected by a belt 66^a to the driving pulleys 66 mounted on the shaft 64, said belt 66^a also passing around the pulleys 80, 82, and 83. Suitable springs are provided on the pulleys 80, 82, and 83 for keeping the belt 66^a tight at all times.

20 *Front brush operating mechanism.*—In order to polish the front of a shoe, a front brush 87 is provided, said brush being loosely mounted on a shaft 93 and being continuously driven by a belt 91^a passing over a pair of pulleys 89 and 92, said pulley 89 being on a shaft 91, and said pulley 92 being rigidly connected to said front brush 87. The shaft 91 is driven by a belt 89^a passing around a pulley 90 on the shaft 91 and a pulley 88 on the shaft 38, previously described.

In order to raise the front brush 87 out of the way when the side brushes are at the forward part of their travel, the front brush 87 is carried by a pair of rods 94, which are pivoted upon the shaft 93, and are rigidly mounted on the shaft 91. A pair of angularly arranged arms 95 and 96 are also rigidly mounted on the shaft 91, the arm 95 being adapted to be engaged by a lug 79^a on the side brush carriage. The arm 96 is curved and is adapted to be lifted by an arm 97 whenever the user removes his foot from the treadle. This lifting action is accomplished by the action of a spring 97^b. A wire 97^a is connected with the arm 58^a on the rack shaft 17 and serves to pull the front brush 87 down into operating position when the user places his foot on the treadle. A spring 96^a is provided on a shelf 59^c and is adapted to cause the front brush to press upon the front of the shoe at all times, said spring being connected to an extension of the lever 96.

55 The liquid polish for the front brush is supplied by a roller 59^a mounted on the end of a lever 99^a hinged at 59^b to a shelf 59^c. The lever 99^a has a side arm 99 to which is connected a wire 98 secured at its other end to the treadle 1.

60 In order to permit the user of the machine to steady himself, a suitable hand rail 100 may be provided along the bottom of the inclined section E of the casing.

65 While there has been disclosed in this specification one form in which the inven-

tion may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention 75 what is claimed as new and for which it is desired to secure Letters Patent is:

1. In a shoe polishing machine, a casing, means for brushing the sides of a shoe, means for brushing the front of said shoe, means for brushing the heel of said shoe, means for reciprocating said side brushing means along the whole length of said shoe, and means for intermittently raising said front brushing means out of operating position when the side brushing means are at the front of said shoe.

2. In a shoe polishing machine, a casing, means for brushing the sides of a shoe, means for brushing the front of said shoe, means for brushing the heel of said shoe, means for reciprocating said side brushing means along the whole length of said shoe, and means for intermittently lowering said heel brushing means out of operating position when the side brushing means are at the rear of said shoe.

3. In a shoe polishing machine, a casing, means for brushing the sides of a shoe, means for brushing the front of said shoe, means for brushing the heel of said shoe, means for reciprocating said side brushing means along the whole length of said shoe, and means for alternately moving said front brushing means and said heel brushing means out of operating position when the side brushing means are at the front and rear of said shoe respectively.

4. In a shoe polishing machine, a casing, a treadle for supporting a shoe to be polished, a pair of side brushes, a reciprocating frame for sliding said brushes back and forth to operate on the whole length of said shoe, pivotally mounted brushes for shining the front and rear of the shoe respectively, means for continuously rotating all of said brushes, and means for temporarily moving said front and rear brushes out of their operating positions.

5. In a shoe polishing machine, a casing, 120 a shoe supporting treadle, means for brushing the sides of a shoe, means for brushing the front of said shoe, means for brushing the heel of said shoe, means for reciprocating said side brushing means along the whole length of said shoe, and adjustable means for permitting said treadle to be raised and lowered varying distances to correspond to the size of said shoe.

6. In a shoe polishing machine, a casing,

- a treadle for supporting a shoe to be polished, a pair of side brushes, a reciprocating frame for sliding said brushes back and forth to operate on the whole length of said shoe, pivotally mounted brushes for shining the front and rear of the shoe respectively, means for continuously rotating all of said brushes, means for temporarily moving said front and rear brushes out of their operating 5 positions, and a motor for simultaneously rotating all of said brushes.
7. In a shoe polishing machine, a casing, a treadle for supporting a shoe to be polished, a pair of side brushes, a reciprocating 10 frame for sliding said brushes back and forth to operate on the whole length of said shoe, pivotally mounted brushes for shining the front and rear of the shoe respectively, means for continuously rotating all of said brushes, and means for temporarily moving said front and rear 15 brushes out of their operating positions.
15. In a shoe polishing machine, a casing, a treadle for supporting a shoe to be polished, a pair of side brushes, a reciprocating frame for sliding said brushes back and forth to operate on the whole length of said shoe, pivotally mounted brushes for shining the front and rear of the shoe respectively, means for continuously rotating all of said brushes, and means for temporarily moving said front and rear 20 brushes out of their operating positions, and a motor for simultaneously rotating all of said brushes, and means for permitting said motor to operate when the user removes his first foot from the treadle and replaces it with his second 25 foot, and for shutting off said motor when the user removes his second foot from the treadle.
8. In a shoe polishing machine, a casing, a treadle for supporting a shoe to be polished, a pair of side brushes, a reciprocating 30 frame for sliding said brushes back and forth to operate on the whole length of said shoe, pivotally mounted brushes for shining the front and rear of the shoe respectively, and means for temporarily moving said front and rear brushes out of their operating 35 positions, a motor for simultaneously rotating all of said brushes, and a coin-re-
- leased handle for closing the electrical circuit through said motor.
9. In a shoe polishing machine, a casing, a treadle for supporting a shoe to be polished, a pair of side brushes, a reciprocating frame for sliding said brushes back and forth to operate on the whole length of said shoe, brushes for shining the front and rear of the shoe respectively, means for continuously rotating all of said brushes, and means for temporarily moving said front and rear 45 brushes out of their operating positions.
10. In a shoe polishing machine, a casing, a treadle for supporting a shoe to be polished, a pair of side brushes, a reciprocating frame for sliding said brushes back and forth to operate on the whole length of said shoe, brushes for shining the front and rear of the shoe respectively, means for continuously rotating all of said brushes, and means actuated by said reciprocating frame for 50 temporarily moving said front and rear brushes out of their operating positions.
11. In a shoe polishing machine, a casing, a treadle for supporting a shoe to be polished, a pair of side brushes, a reciprocating 55 frame for sliding said brushes back and forth to operate on the whole length of said shoe, brushes for shining the front and rear of the shoe respectively, means for continuously rotating all of said brushes, means for temporarily moving said front and rear brushes out of their operating 60 positions, and means for automatically applying polish to said brushes.

In testimony whereof, I have affixed my 75 signature to this specification.

JOHN L. THOMPSON.
